United States Patent Office

Des. 211,175
Patented May 28, 1968

211,175

COAXIAL CONNECTOR

John Cappon, Willowdale, Ontario, Canada, assignor to
Benco Television Associates (Division of Redifon (Canada) Limited)

Filed Aug. 1, 1967, Ser. No. 8,116

Term of patent 14 years

(Cl. D26—1)

FIG. 1

FIG. 2

FIG. 3

FIG. 4

FIG. 1 is a side view of a coaxial connector;
FIG. 2 is a rear view;
FIG. 3 is a front view; and
FIG. 4 is a perspective view, the threaded portion being shown via draftsman's symbol for convenience of illustration.

I claim:

The ornamental design for a coaxial connector, substantially as shown, and described.
